UNITED STATES PATENT OFFICE.

GEORGE D. PARKER, OF RIVERSIDE, CALIFORNIA.

EMPTY-BOX STACKER.

1,293,182.

Specification of Letters Patent.

Patented Feb. 4, 1919.

Application filed July 29, 1918. Serial No. 247,170.

To all whom it may concern:

Be it known that I, GEORGE D. PARKER, a citizen of the United States, residing at Riverside, in the county of Riverside and State of California, have invented certain new and useful Improvements in Empty-Box Stackers, of which the following is a specification.

The present invention relates to an improved stacking apparatus for boxes and more particularly to a type of apparatus adapted for use in stacking the newly constructed and labeled boxes used in a packing-house and in which the fruit is to be packed for shipment.

The object of the present invention is to automatically stack boxes as they are delivered to the stacker from a box dump or elevator or as they may be delivered to the stacker from a conveyer, the boxes being placed upon the conveyer by the sorters or the like, whereby the boxes may be delivered to the packing room in a systematic manner and the space occupied thereby be limited to a minimum.

With the above mentioned and other objects in view the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein:

40 Figure 1 is a view in side elevation of the preferred embodiment of my invention.

Fig. 2 is a view in top plan.

Fig. 3 is a view in detail plan of the conveyer clutch and the operating trip therefor.

45 Fig. 4 is a detail view in side elevation of one of the clutch mechanisms.

Fig. 5 is a sectional view taken on line 5—5 of Fig. 4.

Referring more particularly to the several views of the drawings wherein like characters of reference designate corresponding parts, 1, indicates a suitable supporting member and to the same is secured a pair of brackets 2, which pivotally support one end 55 of a suitable box elevating frame, comprising parallel spaced side members 3 from one end

of which, extend the angularly disposed arms 4 and the foot members 5 which are disposed upwardly, preferably at right angles to the side members 3 when said members lie in a horizontal plane as in the drawing. The members 3 lie preferably when in horizontal position adjacent suitable box supporting members 3'. Pivotally connected to the arms 4, through links 6, are cranks 8 carried by a hub 9, keyed to rotate with a shaft 10 journaled at its ends in suitable bearings, the shaft being driven by a suitable gear 11 operated by a power pinion 12. The shaft is capable of free rotation within the gear 11 but is adapted to be interlocked therewith by a suitable clutch mechanism illustrated in Figs. 4 and 5 of the drawings, and preferably constructed in the following manner: The hub 13 of the clutch is preferably cored and carries a serrated ring 15 within which is received a clutch hub 16, keyed to rotate with the shaft 10, the clutch hub on its outer surface is provided with a recess 18, in which is mounted a dog 19, pivotally supported at its outer end as at 20, and the free end of said dog being forced outwardly as in Fig. 5 of the drawings, by a spring 21. On the reception of the free end of the dog 19 in one of the serrations of the ring 15 the shaft 10 and the gear 11 are locked to rotate in unison, however in this device only a single rotation of these elements at intermittent intervals is desired, the same being controlled by a mechanism hereinafter described.

The side members 3 of the frame normally lie in a horizontal position, as in the drawings, and when in this position, the emptied boxes to be stacked are fed preferably from the labeling machine thereto by the following mechanism: The boxes are placed preferably by an attendant or the same may be positioned by automatic mechanism on an endless conveyer 22, disposed in line with the frame and having spaced conveyer bars 23 on the outer surface thereof, said conveyer at one end operating over a roller 24 carried by a shaft 25, journaled in suitable bearings and said shaft carries on its end a drive sprocket 26, provided with a hub 27, of similar construction to that illustrated in Figs. 4 and 5 of the drawings and employed in connection with the gear 11. Within this hub is positioned a clutch mechanism similar to that illustrated in Figs. 4 and 5 of the

drawings and co-operating with the gear 11. A description of this clutch in connection with the conveyer belt 22 is not thought to be necessary, the purpose of the clutch being 5 to provide intermittent movement for the belt 22 when the frame is in a certain position. A trip mechanism for operating the clutch is constructed in the following manner: A trip finger 28 is positioned with its 10 free end adjacent the pawl 19 of the conveyer clutch, said finger being provided with a beveled surface 29, positioned in the direction of rotation of the shaft 25, said finger being connected to one member of 15 a bell-crank 30. The other end of the bell-crank is connected by a link 31 with one member of another bell-crank 31' of the box lifting frame and the free end of the latter bell-crank is downwardly depressed 20 by the weight of the frame when said frame is in horizontal position, withdrawing the trip member 28 from within the path of movement or rotation of the dog 19 thereby permitting continuous movement 25 of the conveyer belt 22 during such time as the frame is in horizontal position the boxes as received on the belt 22 are conveyed thereby onto the side rails or member 3 of the frame, the boxes within their 30 side walls in engagement and the last conveyed box conveying those on the frame longitudinally thereof until the foremost boxes contact with the foot member 5, the frame now being filled to its capacity with 35 empty boxes. As the foremost contacts with the foot member 5, the same rests on the trip lever 31², pivotally mounted to a support as at 32 and connected at its lower end through a link 33, with one end of a 40 bell-crank 34 fulcrumed as at 35, the free end of said bell-crank being adapted for movement into the path of rotation of the dog 19, thus it will be apparent that on the tipping of the arm 32 of the foremost box 45 contacting with the foot 5, the free end of the bell-crank 34 is withdrawn from contact with the dog 19 permitting the spring 21 to force the dog upwardly to cause a simultaneous movement of the gear 11 and 50 shaft 10 which movement pivots the frame on the support 2, raising the free end thereof to the dotted line position Fig. 2 of the drawing. This movement enables the spring 36 to elevate the free end of bell- 55 crank 30 and cause a disengagement of the dog 19 from the hub 27 of the conveyer belt drive, thus arresting the movement of the conveyer belt. As in the drawing, the movement of the frame is slightly beyond 60 a vertical position, at which time the boxes as supported by the foot member 5 are deposited on a suitable empty box receiving truck 37, capable of being positioned between the supports 2 and movable on small 65 casters 38, the depositing of the boxes in

stacked formation upon the truck causes a slight movement of the truck away from the elevated frame providing a space for the reception of the next stack of boxes received on the side members 3 of the frame. 70 The release of the boxes from the frame when the same is in its lifted position relieves pressure from the trip member 31 and permits the weight of the trip 31² to move the free end of the bell-crank 34 connected therewith into the path of movement of the dog 19, and as the gear 11 completes its revolution lowering the frame to a horizontal position the dog 19 is released from its engaged serration permitting the 80 shaft 10 to remain idle. This lowering of the frame to horizontal position also throws the clutch mechanism associated with the conveyer 22 into position to cause the operation of the conveyer. 85

From my present construction it will be apparent that the conveying of the boxes to the stacker, the operation of the stacker to deliver the boxes to the conveying truck and the return of the stacker to normal position are all automatic movements and it is only necessary that means be provided for placing the boxes on the conveyer and for removing the truck as the same is filled with emptied boxes. 95

Having thus described my invention, what I claim is:

1. An apparatus for receiving and stacking receptacles in vertical unit rows, comprising a horizontally disposed frame fulcrumed at one end and provided at its fulcrum end with a lateral unit row supporting projection, a receptacle unit row receiving member positioned adjacent the fulcrumed end of said frame for successively receiving the vertical unit rows of receptacles from said frame, means for successively feeding receptacles onto the free end of said frame to form thereon a horizontal row of receptacles, and receptacle controlled means thrown into operation on the completion of the formation of a horizontal row of receptacles on said frame for causing movement of said frame on its fulcrum to raise said horizontal row of receptacles to substantially vertical position to discharge said receptacles therefrom in a vertical row onto said receiving member and for returning said frame to horizontal position. 105

2. An apparatus for receiving and stacking receptacles in vertical unit rows, comprising a horizontally disposed frame fulcrumed at one end and provided at its fulcrum end with a lateral projection, a receptacle unit row receiving member positioned adjacent the fulcrumed end of said frame for successively receiving the vertical unit rows of receptacles from said frame, means for successively feeding receptacles onto the free end of said frame to form thereon a hori- 110

- zontal row of receptacles, means controlled by the receptacles positioned on said frame for causing movement of said frame on its fulcrum to raise said horizontal row of receptacles to substantially vertical position to discharge said receptacles therefrom in a vertical row onto said receiving member and for returning said frame to horizontal position, and means for interrupting the operation of the receptacle feeding means during the movement of said frame.
3. An apparatus for receiving and stacking receptacles in vertical unit rows, comprising a horizontally disposed frame fulcrumed at one end and provided at its fulcrum end with a lateral projection, a receptacle unit row receiving member positioned adjacent the fulcrumed end of said frame for successively receiving the vertical unit rows of receptacles from said frame, means for successively feeding receptacles onto the free end of said frame to form thereon a horizontal row of receptacles, controlled means for causing movement of said frame on its fulcrum to raise said horizontal row of receptacles to substantially vertical position to discharge said receptacles therefrom in a vertical row onto said receiving member and for returning said frame to horizontal position, and means controlled by the movement of said frame for interrupting the feeding of receptacles to said frame during the raising and lowering of the free end thereof.
4. An apparatus for receiving and stacking receptacles in vertical unit rows, comprising a horizontally disposed frame fulcrumed at one end and provided at its fulcrum end with a lateral projection, a receptacle unit row receiving member positioned adjacent the fulcrumed end of said frame for successively receiving the vertical unit rows of receptacles from said frame, means for successively feeding receptacles onto the free end of said frame to form thereon a horizontal row of receptacles, and intermittently operated means controlled by the receptacles positioned on said frame for causing movement of said frame on its fulcrum to raise said horizontal row of receptacles to substantially vertical position to discharge said receptacles therefrom in a vertical row onto said receiving member and for returning said frame to horizontal position.
5. An apparatus for receiving and stacking receptacles in vertical unit rows, comprising a horizontally disposed frame fulcrumed at one end and provided at its fulcrum end with a lateral projection, a receptacle unit row receiving member positioned adjacent the fulcrumed end of said frame for successively receiving the vertical unit rows of receptacles from said frame, means for successively feeding receptacles onto the free end of said frame to form thereon a horizontal row of receptacles, and
- means operated by the foremost receptacle of a given row on the completion of the said row of receptacles on said frame for causing movement of said frame on its fulcrum to raise said horizontal row of receptacles to substantially vertical position to discharge said receptacles therefrom in a vertical row onto said receiving member and for returning said frame to horizontal position.
6. An apparatus for receiving receptacles deposited thereon in a horizontal row and for stacking the same in a vertical row unit, the same comprising a horizontally disposed frame fulcrumed at one end and provided at its fulcrum end with a lateral projection, a receptacle unit row receiving truck positioned adjacent the fulcrum end of said frame for successively receiving the vertical unit rows of receptacles from said frame, an endless conveyor for depositing receptacles onto said frame and for causing movement thereof longitudinally of said frame to force the foremost receptacle of said horizontal row into contact with said lateral projection, and means thrown into operation by the foremost receptacle of a formed row on said frame for causing movement of said frame on its fulcrum to raise the row of receptacles thereon to substantially vertical position and to discharge the same therefrom in a vertical row onto said truck and for returning said frame to horizontal position.
7. An apparatus for receiving receptacles deposited thereon in a horizontal row and for stacking the same in a vertical row unit, the same comprising a horizontally disposed frame fulcrumed at one end and provided at its fulcrum end with a lateral projection, a receptacle unit row receiving truck positioned adjacent the fulcrum end of said frame for successively receiving the vertical unit rows of receptacles from said frame, means for depositing receptacles successively onto said frame and for causing movement thereof longitudinally of said frame to force the foremost receptacle of said horizontal row into contact with said lateral projection, actuating means for raising and lowering said frame on the completion of a row of boxes thereon, and a trip member actuated by a receptacle on said frame for throwing said actuating means into operation.
8. An apparatus for the described purpose comprising an elongated frame fulcrumed at one end for pivotal movement on a horizontal axis, an endless conveyor for feeding receptacles onto said frame in a longitudinal row when said frame is in substantially horizontal position, actuating means for raising said frame from horizontal to vertical position on the completion of a row of receptacles thereon, a trip member actuated by a receptacle on said frame for

throwing said actuating means into operation, means for receiving the vertical row of receptacles as a unit from said frame when the same is in substantially vertical position, and means for interrupting the operation of said conveyer during such time as said frame is not in horizontal position.

In testimony whereof I have signed my name to this specification in the presence of two subscribing witnesses.
